UNITED STATES PATENT OFFICE.

WARREN E. COOMBS, OF BOSTON, MASSACHUSETTS, AND CHESTER D. TURNER, OF MANCHESTER, NEW HAMPSHIRE, ASSIGNEES TO UNITED SHOE MACHINERY CORPORATION, OF PATERSON, NEW JERSEY, A CORPORATION OF NEW JERSEY.

SHOE RACK.

Application filed August 25, 1924. Serial No. 733,970.

To all whom it may concern:

Be it known that we, WARREN E. COOMBS and CHESTER D. TURNER, citizens of the United States, and residing at Boston, in the county of Suffolk and Commonwealth of Massachusetts, and Manchester, in the county of Hillsborough and State of New Hampshire, respectively, have invented certain Improvements in Shoe Racks, of which 10 the following description in connection with the accompanying drawings, is a specification, like reference characters on the drawings indicating like parts in the several figures.

15 This invention relates to shoe racks such as are used to carry shoes from one part of a factory to another for the performance of various shoemaking operations, and to hold shoes between operations. The invention is illustrated as embodied in what is known as a pin rack of the type having members, termed "pins", for supporting and maintaining bottom side up in spaced relation shoes the tops of which are received in slots between the pins.

20 In one form of pin rack commonly used heretofore, each shoe is supported by two round pins which engage that shoe only. In another form which has been extensively used, substantially half as many pins afford the same shoe-holding capacity, each pin comprising a member, frequently termed a "paddle", having one side in engagement with one shoe and the other side in engagement with another shoe.

25 Whatever the form of rack, it is important that it take up as little factory floor space as is practicable with due regard to supporting the shoes without liability of 30 their rubbing together either when they are taken from or replaced on the racks, or as they are jostled in moving the racks from place to place. Hundreds of shoe racks, and in the larger shoe factories thousands 35 of racks, are required to handle the factory output. Necessarily, therefore, these racks take up a large amount of floor space. As such racks have been constructed heretofore, they have so congested factory floors 40 as to constitute a serious problem. Consequently, any appreciable economy of floor space which can be effected by constructing racks more compactly represents a large saving to the shoe manufacturer, providing

it can be accomplished without liability of 55 damaging shoes.

The problem of thus economizing floor space is aggravated by the fact that in the manufacture of shoes, particularly shoes of the better grades, it is common practice 60 to rack shoes in pairs to prevent separation of the shoes of a pair, and to facilitate manufacturing uniformity for each pair. In pin racks as heretofore constructed, the center lines of the slots between adjacent shoe- 65 supporting pins have been uniformly spaced. Consequently, when shoes are placed in such a rack in pairs, that is, with corresponding edges of the shoes of a pair adjacent, if sufficient clearance is allowed between the 70 pins to insure that adjacent outside shoe forepart surfaces will not rub together, there will be unnecessary space between adjacent inside forepart surfaces due to characteristic differences in shape between the inside 75 and outside contours of shoes.

In view of the foregoing, the present invention provides an improved shoe rack in which wider pins each of sufficient width to position shoes with their outer edges closely 80 adjacent but out of contact alternate with narrower pins each of sufficient width to position shoes with their inner edges closely adjacent but out of contact.

85 Preferably, and as herein illustrated, the rack is provided with a series of pins each engaging two shoes and comprising relatively wide pins alternating with narrower pins constructed and arranged to position 90 shoes in pairs with corresponding edges of successive shoes closely adjacent but out of contact. Thus the illustrated rack is as compact as possible consistently with avoiding liability of injury to adjacent shoes by 95 rubbing together.

These and other features of the invention, comprising certain combinations and arrangements of parts, will be understood from the following description of a preferred embodiment thereof selected for purposes of illustration and shown in the accompanying drawings, in which

Fig. 1 is a front elevation of a rack embodying the present invention;

Fig. 2 is an enlarged sectional view taken 105 on the line 2-2 of Fig. 1;

Fig. 3 is a detail perspective view illustrating the pin construction; and

Fig. 4 is a diagrammatic plan view of the pin bar and shoes supported thereby.

The illustrated rack comprises a bottom frame 10, end frames 12, 14, casters 16, braces 18, and bumpers 20, all of which are of well-known construction and need not further be described. The end frames 12 and 14 in the disclosed construction are provided with angle bars 22 for supporting the pin bars 24, there being one bar 22 in the end of the frame at each end of each pin bar, and there being an arbitrary number of pin bars in the rack as a whole. Two longitudinal bars 26, 28, formed preferably of steel, are bolted or riveted at their ends to the corresponding bars 22. For supporting shoes, each of the pin bars 24 carries a series of flat paddle pins 30, 32. The paddles 30 are substantially wider than the paddles 32 and the two types are arranged in alternation along the pin bar, as shown in Fig. 1 and Fig. 3. The edges 34 of these paddles are slotted parallel to their length so that these longitudinal slots in each adjacent pair of pins face each other. In these slots is mounted a short metal bar 40 which bridges over from each pin to the next and which is bolted to the bars 26 and 28 at its ends as shown at 42 in Fig. 2. As shown in Fig. 3, the bottoms of the pins or paddles are recessed to receive the bars 26 and 28 upon which they lie and to which they are fastened by the bars 40 in the slots in their sides. The structure thus described securely fastens the pins to the longitudinally extending bars 26, 28 and also permits easy removal and replacement of a broken pin. Advantageously, a toe rest bar 44 is provided extending lengthwise of the rack near the inner ends of the slots 46 formed by each two adjacent pins.

In the illustrated use of the rack, the shoes are placed bottom side up, each of the paddles 30, 32 engaging and partly supporting two shoes, and the tops of the shoes being received in the slots 46, while the foreparts of the shoe uppers engage and rest upon the toe rest bar 44. When the shoes are mounted upon lasts, as indicated by dotted line in Fig. 2, the cones of the lasts are received in the slots 46. It will be observed that while the rear portions of the sides of the paddles are straight and parallel, as indicated at 34, the forward portions of the sides of the paddles are concave, as indicated at 36. The concave shape of the sides of the paddles, supplemented by sloping the bars 22 downwardly from the front to the back of the rack, serves to prevent the shoes from being jostled out of supporting engagement with the paddles as the rack is moved from place to place in the factory.

The advantages of the present invention are well illustrated by Fig. 4, which shows a plan view of five pins with a diagrammatic showing of shoes supported in the slots be-

tween the pins. It will be observed that in the illustrated construction each of the paddle pins has edges shaped to engage the tops of the shoes, the narrower paddle pins being of sufficient width to position shoes with their inner edges closely adjacent but out of contact, and the wider paddle pins being of sufficient width to position shoes with their outer edges adjacent but out of contact, thereby providing for supporting shoes in pairs with the shoes of each pair side by side. Thus the illustrated alternation of the wide pins 30 and narrow pins 32 and the consequent variations in the separation of the center lines of the slots 46 are effective to position the outer edges of the shoes of each pair closely adjacent but out of contact and to position the inner edges of the shoes of each pair closely adjacent to but out of contact with the inner edges of the adjacent shoes.

In the arrangement illustrated in Fig. 4, the second and third of the four shoes therein shown constitute a pair of shoes. It is obvious, however, that, instead of having the end paddles of each series of paddles each equivalent to one-half of a narrow paddle, as illustrated in Figs. 1 and 3 of the drawings, each end paddle of the series may be the equivalent of one-half of a wide paddle. In that case, the shoes of each pair will be arranged with their inner edges adjacent and with their outer edges adjacent to the outer edges of shoes of adjacent pairs. In either case the advantages of the invention are equally obtained in essentially the same way. Thus adequate room is provided for the shoes without liability of their rubbing together, and at the same time no room is wasted, as has been the case in heretofore existing racks in which the shoe-receiving slots were uniformly spaced along the pin bars 24.

The front ends of the slots 38 may advantageously be filled by wooden plugs 48, as shown in Figs. 1 and 2, the bars 40 being substantially shorter than the slots in the wooden pins in order to avoid danger of contact between the shoes and any metal parts of the rack.

While the invention is disclosed in connection with a paddle rack, it is not to be understood as limited thereto, as its advantages can be equally well secured in other types of rack, in particular the round pin type of rack discussed above.

Having described our invention, what we claim as new and desire to secure by Letters Patent of the United States is:

1. In a shoe rack, a series of pins for supporting shoes and maintaining them in spaced relation comprising wider pins each of sufficient width to position shoes with their outer edges closely adjacent but out of contact alternating with narrower pins

each of sufficient width to position shoes with their inner edges closely adjacent but out of contact.

2. In a shoe rack, a series of pins for supporting shoes and maintaining them in spaced relation comprising wider pins each of sufficient width and suitably arranged to engage two shoes and position said shoes with their outer edges closely adjacent but out of contact, alternating with narrower pins each of sufficient width and suitably arranged to engage two shoes and position said shoes with their inner edges closely adjacent but out of contact.

15 3. A shoe rack comprising a frame, and a series of pins carried by the frame and projecting therefrom for supporting and maintaining in spaced relation shoes the tops of which are received in slots between the pins, the series of pins comprising relatively wide pins alternating with narrower pins constructed and arranged to position shoes in pairs with corresponding edges of successive shoes closely adjacent but out of contact.

25 4. In a shoe rack, a frame, and a series of flat paddle pins of different widths pro-

jecting from the frame, each of said paddle pins having edges shaped to engage the tops of shoes whereby adjacent edges of adjacent paddle pins form a slot to receive and support an inverted shoe, the narrower paddle pins being of sufficient width to position shoes with their inner edges closely adjacent but out of contact, the wider paddle pins being of sufficient width to position shoes with their outer edges closely adjacent but out of contact, and said narrower paddle pins alternating with said wider paddle pins, with pins at each end of the series of sufficient width to support one shoe only and having their outer edges closely adjacent to the ends of the frame, thereby providing a rack of minimum dimensions adapted for supporting shoes in pairs, with the shoes of each pair side by side.

In testimony whereof I, the said WARREN E. COOMBES, have signed my name to this specification.

WARREN E. COOMBES. 50

In testimony whereof I, the said CHESTER D. TURNER, have signed my name to this specification.

CHESTER D. TURNER.
